Rufus Bowles.

UNITED STATES PATENT OFFICE.

FLINT W. WRIGHT, OF WORCESTER, MASSACHUSETTS, ASSIGNOR OF ONE-
THIRD TO HENRY A. FOWLER, OF SAME PLACE.

MAILING-WRAPPER.

SPECIFICATION forming part of Letters Patent No. 544,270, dated August 6, 1895.

Application filed October 23, 1894. Serial No. 526,697. (No model.)

To all whom it may concern:

Be it known that I, FLINT W. WRIGHT, a citizen of the United States, and a resident of Worcester, in the county of Worcester and State of Massachusetts, have invented a new and useful Improvement in Mailing-Wrappers, of which the following is a specification, reference being had to the accompanying drawings, forming part of the same, in which—

Figure 1 represents a view of a mailing-wrapper embodying my invention, a portion of the paper cover being shown as extended in order to disclose one end of the cardboard inclosed therein. Fig. 2 represents a transverse sectional view on a larger scale of a portion of the wrapper. Fig. 3 represents a transverse sectional view of the completed wrapper after it has been rolled up, and Fig. 4 represents a transverse sectional view of a strip of cardboard before it is inclosed in its paper cover.

Similar letters refer to like parts in the different figures.

Referring to the accompanying drawings, A denotes a sheet of firm paper one-half of which is represented as extended at A'. One end of the sheet is square and the opposite end is preferably pointed or triangular, as at A², and the tip of the pointed end can be provided with a gummed section, as at A³.

Upon the central portion of the paper sheet A when it is extended is placed a sheet B of firm cardboard, which is prepared by slitting the cardboard except at its ends, where it is left united as represented at B', Fig. 1, one end of the cardboard-sheet being shown in said Fig. 1, the end not shown being a duplicate of the end disclosed. The cardboard is preferably cut entirely through, forming slits B² nearly the entire length of the cardboard, but left entire at each of its ends, as at B', so the separate strips of the cardboard at B² are held parallel with each other and at a uniform distance apart. The cardboard is also

skived at its opposite edges, as at C and C', forming beveled edges, preferably upon opposite sides of the cardboard. A coat of glue or paste is applied to the opposite sides of the cardboard, which is placed upon the sheet of paper in the position shown in Fig. 1, and the square end of the sheet is then folded over

and upon the glued piece of cardboard, as represented in the left-hand half of Fig. 1, thereby inclosing the cardboard and adhering firmly to both sides thereof.

The slits B² are cut just wide enough so that when the wrapper is rolled into a circular form, as shown in Fig. 3, the edges D of the strips B² will come into contact with each other or with the folds E of the paper cover, causing the edges D to crowd against each other and form a mutual support, so as to resist outside pressure and form a tube in which matter can be rolled for transmission through the mails with safety.

By reference to the sectional view shown in Fig. 3, it will be observed that the contact of the strips B² is at the inner corners, while the outer fold of the paper cover serves to hold the strips together. The skived edges C and C' fold together and prevent too great thickness at the folded edges.

By leaving the cardboard united at its ends, as at B', the strip of cardboard can be placed in position and folded into the paper cover without any regard to the distance between the strips B², as these strips are held in place parallel with each other and at the required distance apart, by the united ends B'.

In the above-described wrapper it is necessary that the strips of cardboard possess sufficiently firm and unyielding edges and that the strips be arranged upon the sheet of paper at substantially a uniform distance apart and with the proper space between the strips, so the inner corners of the contiguous strips will crowd against each other when the wrapper is rolled, thereby forming a tube which is capable of resisting outside pressure tending to collapse the tube or reduce its diameter, each of the strips, when the wrapper has been rolled into the form of a tube, forming a portion of a continuous arch capable in itself of resisting pressure.

What I claim as my invention, and desire to secure by Letters Patent, is—

1. As an article of manufacture the within described mailing wrapper comprising the paper cover A, and an inclosed cardboard strip B attached to said cover, said cardboard strip having slits B², and being united at its ends, whereby the edges of said slits are main-

tained parallel and at a uniform distance apart, as and for the purpose specified.

2. As an article of manufacture, a mailing wrapper consisting of a cover A and a piece of cardboard B attached to said cover, said cardboard having a series of slits by which the cardboard is divided into parallel strips, said strips being left united through a portion of their length, whereby said strips are

hinged together and also maintained parallel to and at a uniform distance apart, substantially as described.

Dated this 20th day of October, 1894.

FLINT W. WRIGHT.
